(57) **CLAIM**

We claim the ornamental design for a charger for head mounted audio-visual display system, as shown and described.

DESCRIPTION

FIG. 1 is a rear top perspective view of our design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depicting portions of the charger for head mounted audio-visual display system are included for the purpose of illustrating environmental structure and form no part of the claimed design.

1 Claim, 8 Drawing Sheets
